UNITED STATES PATENT OFFICE

RAFAEL EDUARDO DOMINGO MARADEI, OF BUENOS AIRES, ARGENTINA

ELECTRIC LAMP

Application filed June 5, 1929, Serial No. 368,630, and in Argentina January 29, 1929.

My invention has reference to a new type of electric lamp for lighting purposes, having a bronze base and filament, a glass globe, and internal parts, all of which are renewable, together with a supplementary machine or connector by which a vacuum may be created in the said lamp, with any of the current types of vacuum pumps.

In order to make my invention clear, descriptive drawings are attached, in which:—

Figure 1 shows a side view of the internal metal part of the lamp base, combined with the glass core and filament supports.

Figure 2 is a view of the same parts as seen from above.

Figure 3 is a longitudinal section through the same parts, when assembled.

Figure 4 is a screw plug attachment which fits into the upper part of the lamp base already referred to.

Figure 5 shows two views of the glass core and filament supports as seen from the side and in part section.

Figure 6 is a longitudinal section through the same part, independently.

Figure 7 is a longitudinal section through the valve piston which closes the lamp once a vacuum has been created.

Figure 8 is a view in plan of the same part.

Figure 9 shows the rubber cover-piston which hermetically seals the lamp.

Figure 10 is a view in plan of the former.

Figure 11 shows the piston-valve spring.

Figure 12 shows a side view of the inner part of the lamp socket, independently.

Figure 13 is a cross section through the former.

Figure 14 shows a longitudinal section through the lamp base when attached to the supplementary apparatus at the moment when a vacuum is being created.

Figure 15 shows these two parts in their normal state: separated, after a vacuum has been created.

Figure 16 shows an outside view of the lamp base, complete.

Figure 17 is a cross section through the former.

Figure 18 is a longitudinal sectional view of the lamp, complete.

In all the figures mentioned, the same letters indicate the same or similar parts.

The lamp is made up of the following parts:

An outer shell P'' of bronze or other suitable metal forming the lamp base, the lower end of which is threaded to standard pitch, thus allowing the lamp to be screwed into any lamp holder socket.

The lower part of said metal lamp base is expanded to a bell mouth into which the lamp globe or bulb fits, and to which it is attached by a special arrangement of four eccentric lever clips P''' which act upon an internal ring Q'' of rubber or asbestos, of suitable shape.

The special shape of the said internal ring and that of the lamp globe rim, when once the four eccentric lever clips P''' have been adjusted and fitted into the four corresponding grooves X'' in the globe, make an absolutely air tight connection. In order to facilitate the action of the said lever clips and to seal the connection perfectly, a series of parallel slots Q'''' have been cut in the bell-mouth base, forming vanes through which a wire ring H' is run. The said slots make the base rim more flexible and so allow it to adapt itself more easily and to fit more closely to the asbestos or rubber ring Q'' .

The inner part of the said lamp base is composed of the following: A cylindrical metal shell A , in the upper part of which, and near the end, is a circular groove O , the only aperture at this end being that into which the screw-plug D is inserted and screwed up.

The lower part of the said cylindrical metal shell is entirely open, having on opposite sides, several slots E , into which fit

the stops E' on the metal covering of the glass core I supporting the lamp filament. The said cylindrical metal shell has a small circular hole B near its upper end through which the air may pass.

5 A metal piston F is fitted to the inside of the said cylindrical shell and is actuated by a spring which keeps it pressed against the rubber washer G, which, in turn, has a hole 10 in the centre into which the head N of the piston fits. The aperture left in the cylinder cover serves as a socket into which the screw-plug D may be screwed.

15 The glass core I fits inside the cylindrical metal shell and is secured to same by the bayonet-clutch slots at E, the said core forming the base of the glass rod filament supports Y''' and having a metal crown J with fitting stops E'. A cylindrical cavity L is 20 formed in the centre of the glass core in which the rod H attached to the piston F may slide.

25 Between the external threaded shell P'' and the cylinder A already described, a filling of glass R'' or other insulating material is inserted, thus making a close and substantial bond between these two parts, but through the said filling an air duct R''' is left which establishes a communication between the inside of the lamp globe and the cylinder A by means of the air passage B.

30 The upper part of the lamp base is covered with black glass or other suitable insulating material P, which hermetically seals the connection between the outer shell P'' and the cylinder A and at the same time prevents any electric current passing from one of the said parts to the other.

35 The glass core I supporting the filament carrier is fitted with a metal ring K near the point of contact with the cylinder, on which metal ring rests a flexible contact strip of metal V'', one end of which is soldered to the inside wall of the threaded lamp base P'' the said contact strip making the connection between the said threaded lamp base and one end of the filament X''' which is soldered to the metal ring K. The other end of the filament which is soldered to the 50 metal crown J establishes contact through the cylinder walls A to the screw-plug D.

40 The glass rod filament support Y''' which is an extension of the glass core I may be of any of the types in current use.

45 The lamp globe proper may also be of any of the current types, but the mouth of same where it is attached to the lamp base, must be specially shaped for this, and be sufficiently wide to allow for its removal or application without fear of its coming into contact with the filament supporting apparatus.

50 Both the lamp globe and the mouth of same may be altered in design to suit the shape of the filament employed, and whether this

is fitted longitudinally, transversely or in a circular form, the lamp globe taking on the outward shape to correspond, as occurs with the ordinary lamps.

55 The supplementary apparatus or connector with which the requisite vacuum is created in the lamp globe, is made up as follows:

60 Two hollow metal cylinders—Figs. 14 and 15—letters Q and T', work one inside the other.

65 The outer cylinder Q slides in two guide-blocks Q', the said cylinder having near its centre a rim R' which serves to retain the steel spring R between the said rim and one of the guide blocks Q'. The same outer cylinder Q has on one end a rubber ring P' which fits into the screw socket C of the lamp base, and the opposite end of the said cylinder is fitted with a rubber washer T'' and over this washer a metal cap T''' is fitted, which compresses the said rubber washer.

70 Each of the two cylinders already mentioned is fitted with a fork S and T in which two metal rods S' and S'' are hinged, the said rods being actuated by the eccentric sheaves Y'' and Z, respectively, which impart a reciprocating movement to the two cylinders.

75 One end of the inner cylinder T' is entirely open and on to this opening the end of the rubber pipe V leading from the vacuum pump is attached; the other end of this cylinder is closed except for a small hole S''' on one side, through which the air absorbed by the vacuum pump passes, the said end fitting 100 into the cylinder A in the lamp base through the opening C.

80 The ends of the rods S' and X are each fitted with a roller, these rollers running on the outer eccentric sheave Y'' and the inner eccentric sheave Z respectively.

85 The rod S' besides being supported by the fork S is further sustained by an extra guide block V'. Other two rods S'' and Y work in the fixed bearings X' and X'', the whole of the said rods combining to give the cylinders Q and T' the necessary reciprocating motion transmitted by the eccentric sheaves Y'' and Z. The shaft Z' which drives the eccentric sheaves, derives its motion from any suitable machine or motor, and the bearing blocks Q', V', X' and X'' must be suitably arranged 115 so as to conform to the general lay-out of the rest of the machine.

90 It is also evident that some method must be adopted for holding the lamp base and the globe while the vacuum is being created and this may be done either by the use of clamps, vices or any other suitable devices.

95 In the special cases where gas is to be injected into the interior of certain lamps, the same inner cylinder T' acts as an injector once a vacuum has been created in the lamp globe, it only being necessary for another rubber pipe to be connected to the one V already de-

scribed. In such case each pipe would have to be fitted with the ordinary automatic appliances designed to open and close as required when creating a vacuum and to act inversely when injecting gas.

The practical results to be obtained from the use of this lamp and the supplementary connector are as follows:

When a lamp filament burns out or breaks, all that is necessary is to lower the eccentric clip levers P''' to the position P'''' —see Fig. 16—and by so doing, the pressure brought to bear on the inner rubber or asbestos ring Q'' by the vanes Q''' is relieved by the action 15 of the wire ring H —Fig. 18.

The lamp globe may now be detached from the metallic base, and the glass rod Y''' —Fig. 13—and the tentacles which hold the filament will be left uncovered. The filament may 20 then be renewed, and once this is done, the lamp globe is again placed in position and secured by the eccentric clip levers, being brought back to the position P''' . This being done, the screw-plug D is removed from 25 the cylinder A and the end of the connector applied to the cavity as shown in Fig. 15.

The connector is now set in motion, and by means of the outer eccentric sheave Y'' , pressure will be brought to bear upon the roller 30 Y' which will be transmitted to the rod S' . Since this rod is attached to the cylinder Q by means of the fork S , the said cylinder will compress the spring R and move forward bodily until the end enters the socket C in the 35 lamp base cylinder A as shown in Figure 14. The end of the outer connector cylinder Q which fits into the socket in the end of the lamp base cylinder A , carries a rubber ring P' —Figure 14—which entirely prevents any 40 air entering said cylinder A . Once the operation just described has been completed, the inner eccentric sheave Z acts upon the roller carried on the end of the rod Y , transmitting motion to the rod X , this in turn 45 multiplying the effect and transmitting same through the rod S'' , causes the inner cylinder T' to advance after cylinder Q has come to rest.

The inner cylinder T' of the connector then 50 enters the lamp base cylinder A , the pressure transmitted, as just described, overcoming the resistance offered by the spring N , and causing the piston rod H —Figure 3—to slide into the cavity L in the glass core I . As 55 the piston F is welded or otherwise firmly attached to the rod H and the rubber washer G is held by the piston head N , all these parts are displaced together by the pressure exercised by the connector cylinder T' , 60 and travel along the lamp-base cylinder A until the opening B —Figure 14—is uncovered, thereby establishing a communication to the inside of the lamp globe through the air duct R''' —Figures 15 and 18.

65 Once the piston occupies the position shown

in Figure 14, the vacuum pump comes into action, and by means of the rubber pipe V attached to the end of the inner connector cylinder T' the air contained in the lamp globe is exhausted, passing through the small 70 hole S''' found in the side of the said inner cylinder near its inner end.

A vacuum having now been formed in the lamp globe, the connector is again brought into play and the second phase of the work 75 commenced by the eccentric sheaves is now completed by first drawing out the inner connector cylinder T' and so allowing the spring N to again expand—Figures 3, 11 and 14—and by so doing, force the piston back 80 to its original position and prevent any air entering by the opening C —Figure 4. Once the inner connector cylinder T' has been entirely removed—Figure 15—the action of the outer eccentric sheave Y'' will also remove cylinder Q , and all that is then required to put the lamp in working order is to screw in the screw-plug D , Figs. 1 and 4. The eccentric Y'' in Fig. 15 is shown reduced in 85 size from that in Fig. 14. The design of the eccentrics depends upon the rest of the mechanical system and the disposition of the lamp with respect to the connector.

Should it be the glass rod Y''' instead, which requires renewal—Figure 18—this 90 may be done in the following manner: After removing the lamp globe Z'' from the metallic base as has been already described, the glass core I is taken and pressed firmly against the lamp base, upwards, giving it a 95 slight turn to the left at the same time so as to detach it from the stops E' —Figures 1, 2 and 5—which are carried by the metal crown J —Figures 3, 5 and 6—and engage in the slots E in the lamp-base cylinder A . A new 100 or repaired glass core is then inserted, the lamp assembled and a vacuum created as already described.

Any of the lamp parts which may have 105 been broken or damaged, such as the glass globe, the piston, piston-rod, rubber or asbestos ring, contact strip, spring, etc., may be renewed in a similar manner.

The electric contacts completing the circuit and producing light occur as follows: 110 When the lamp is screwed into a lamp holder one pole comes into contact with the screw-plug D —Figure 4—the current then passing through the cylinder walls A up to the metal crown J —Figures 3, 5 and 6—to which one 115 of the wires X''' is soldered.

The opposite pole connects up through the threaded lamp-base P'' , Figures 16, 17 and 18, to which one end of the contact strip V'' is soldered, the other end of said strip making a pressure contact with the metal ring K 120 to which the other wire X''' is soldered.

These two wires are carried in the interior 125 of the glass core I , passing down through this and coming out below to form the two 130

supports on which the lamp filament X''' is stretched.

The benefits and advantages to be gained by the adoption of this type of lamp as invented by me are numerous.

In the first place, the manufacture of this type of lamp could be carried out at a very low cost, if produced in large quantities, and the slight increase in cost which might result over the ordinary type of lamp would be 10 amply compensated for by the number of times the lamp as invented by me could be repaired by the renewal of parts, at a cost which may be considered as insignificant.

15 One of the ordinary lamps, once the filament is broken or burnt out, must necessarily be entirely replaced, while in the case of the lamp of my invention, the lamp is made as good as new with a very small outlay.

20 These advantages are increased still further when dealing with lamps of large size and lighting power, their first cost being quite considerable. The lamp as invented by me could be renewed in part as required at 25 a cost infinitely lower than that of a new lamp complete, as would be necessary with the ordinary type of lamp.

Apart from the causes already mentioned, it is a well known fact that a lamp filament 30 becomes dimmed and loses its brilliance with continued usage, and as the lamp globe gets blackened at the same time, a much duller light than when new is the result. Also, a greater consumption of current results.

35 These drawbacks are very easily overcome by the use of the lamp of my invention, the weakened filament being renewed and the glass globe cleaned up at the same time, with great advantage to the consumer.

40 In a similar manner to that in which the filament may be renewed in the lamp of my invention, any other wasted or damaged part may be renewed at will.

Furthermore, it would not be necessary for 45 the renewal of parts to be confined to the manufacturers of these lamps, since dealers could easily and cheaply acquire a connector as already described, and in conjunction with a vacuum pump could effect renewals 50 and repairs at very low cost.

It is well to note that my invention may be applied to lamps of any shape, colour or design; with either ordinary, large or small screwed bases or of bayonet type as 55 desired, and in accordance with any lamp holder either for direct or alternating current.

It should also be observed that notwithstanding the absolute air tightness of all 60 the parts composing the lamp of my invention, the vacuum formed in the ordinary type of lamp is far from being perfect and is what is generally termed a "partial vacuum".

Having now particularly described and 65 ascertained the nature of the invention and

in what manner the same is to be carried into practice, what I claim is:

1. An electric lamp comprising a base, a hollow shell secured within said base, a globe detachably connected to said base, an aperture in said shell connecting the interior of said shell with the lamp interior, a second aperture in said shell connecting the interior of said shell with the external atmosphere, and a movable valve member normally adapted to close said first named aperture. 70

2. In combination, an electric lamp comprising a base, a shell secured within said base, a globe detachably connected to said base, an aperture in one end of said shell connecting the interior with the outside atmosphere, a passage connecting the interior of said shell with the space included within said base and globe, a valve member normally sealing said aperture, means for yieldably 80

holding said valve member in said position, and a connector for a vacuum pump comprising a set of two cylinders one within the other, means for moving said cylinders relatively to one another, the outer one of said cylinders being provided with an opening for abutting one end of said shell and surrounding said aperture, the inner one of said cylinders being adapted to pass through said aperture and force said valve member from 90 said normal position whereby said aperture is unsealed, an opening in said inner cylinder connecting the interior of said cylinder and the interior of said shell when said inner cylinder is passed through said aperture, and 100 means for connecting the interior of said inner cylinder with a vacuum pump.

3. An electric lamp comprising a metallic base, a metallic shell supported within and electrically insulated from said base, a glass 105 globe detachably connected to said base, a filament support detachably connected to said shell, two contact plates on said filament support, one of said contact plates being in contact with said shell, a contact arm connecting the other of said contact plates with said base, a filament on said filament support the ends of which filament are connected respectively to said two contact plates, a passage extending from the space included with 115 in said globe and base to the exterior of said lamp and movable means for normally sealing said passage.

4. An electric lamp comprising a base, a glass globe, a filament supporting member 120 within said glass globe, means for detachably securing said globe to said base comprising a cylindrical flange on said base, longitudinal notches in said flange forming flexible lugs, a flexible ring surrounding said lugs, means 125 for tensioning said flexible ring and a packing member between said flange and said globe.

5. An electric lamp comprising a metallic base forming one electrical terminal of said 130

lamp, a metal shell supported in and insulated from said base, said shell being closed at one end and provided with an aperture at said end into which aperture a metal button is threaded, said button forming the other electrical terminal of said lamp, a passage connecting the interior of said shell with the interior of said lamp, a filament support and a filament supported thereon provided within said lamp.

10 In testimony whereof I affix my signature.
RAFAEL EDUARDO DOMINGO MARADEI.
